UNITED STATES PATENT OFFICE.

GEORGE A. AMSDEN, OF LITTLETON, MASSACHUSETTS, ASSIGNOR TO THE LAMSON COMPANY, OF BOSTON, MASSACHUSETTS, A CORPORATION OF NEW JERSEY.

CABLE-CARRIER APPARATUS.

1,176,807.

Specification of Letters Patent. Patented Mar. 28, 1916.

Application filed February 5, 1914. Serial No. 816,707.

To all whom it may concern:

Be it known that I, GEORGE A. AMSDEN, a citizen of the United States, residing at Littleton, in the county of Middlesex and State of Massachusetts, have invented certain new and useful Improvements in Cable-Carrier Apparatus, of which the following is a specification.

This invention relates to cable carrier apparatus and more especially, although obviously in certain of its aspects not necessarily, to drop-station apparatus of the character described in my joint application with Rutherford P. Kidder, entitled Drop station for cable carrier apparatus and the like, Serial No. 792,888, filed Oct. 1, 1913.

The present invention has for one of its objects the improvement of the last mentioned apparatus, first by materially reducing the noise of the operation thereof and second by the simplification of parts of said apparatus.

I have further aimed to provide a novel switch the principles of which are broadly new—certainly in so far as the cable carrier art is concerned.

These and other objects of my invention will be hereinafter referred to and the novel elements and combinations of elements whereby said objects are attained will be particularly set forth in the claims appended hereto.

In the drawings which form a part hereof and in which like reference characters designate like parts throughout the several views, I have exemplified certain preferred constructions; but as I am aware of various changes and modifications which may be made herein without departing from the spirit of my invention, I desire to be limited only by the scope of said claims, broadly considered in the light of my disclosure.

Referring to the drawings: Figure 1 is a side elevation, partly broken away, of a cable carrier drop-station embodying my invention. Fig. 2 is an end elevation of said drop-station; a further portion of the track being broken out and the view correspondingly shortened for convenience of illustration. Fig. 3 is a detail view of the grip opening and closing cams at the despatching point in said station. Fig. 4 is a rear elevation of the upper part of said station. Fig. 5 is a plan view of the same. Fig. 6 is a detail section taken on line VI—VI of Fig.

4; drawn to a larger scale. Fig. 7 is a view, similar to Fig. 1, of a modification. Fig. 8 is a detail section taken on line VIII—VIII of Fig. 7. Fig. 9 is a similar section taken on line IX—IX of Fig. 7. Fig. 10 is a detail section taken on line X—X of Fig. 7; and Fig. 11 is a section taken on line XI—XI of Fig. 10.

The detailed description of the station as a whole need be but brief as it is in many respects similar to that described in said joint application; but the features which concern the improved switch or bridge will be considered more fully since the gist of the present invention resides therein and in the combination of such elements with certain other elements of the system as pointed out in the appended claims.

The main-tracks are both preferably so disposed as to convey the carrier with its grip point down; the outgoing track 1 constituting the delivery track to the way stations of which there may be a number, while the incoming track 2, constitute the receiving track for said way stations.

Preferably, but not necessarily, a single endless cable 3, traveling in the directions indicated by arrows, constitutes the means for elevating carriers from the way station or stations to the main receiving track 2, and for thereafter propelling said carriers along said receiving track past the subsequently encountered way stations, while said carriers are *en route* to, for example, the cashier's desk.

The cable at the station shown is preferably looped down and passes around idlers or pulleys 4, 5 and 6, suitably journaled in brackets or other supports. Carriers propelled along track 1 which are intended to be delivered at the station shown are selectively removed from said track in a known manner by a switch 7 and pass down an independent drop track 8 to the station. Carriers to be despatched from the station are inserted at 9, from the left as viewed in Fig. 1, into the track section 10 which delivers to track 2, the upper ends of the rails of track 10 preferably being curved around into substantial tangency with the plane of the track 2, and the despatched carriers traversing these curved rails are preferably cable propelled while so doing.

If the grip of such a carrier be closed at the time of its insertion, as said carrier is

raised by hand to engage it with the elevating section of cable, said grip will be swung open by cam 11. Immediately thereafter cam 12 closes the grip directly on this section of cable, and the carrier moves up toward the switch, broadly designated 13. The latter comprises parallel sections 2' which are, in the present case, actually portions of track 2; and vertical portions 14 which are respectively connected to the portions 2' by brackets 15.

The sections 14 and brackets 15 support the free ends 16 of track parts 2'. In Fig. 6, however, one of the portions 2' has been broken away to show the construction therebeneath. Each end 16 is beveled or cut away on its under side to conform it to the curved upper portion of the corresponding rail of track 10, and the latter terminates at 17; each rail thereof being beveled off horizontally to permit of the passage of the track engaging flanges 18 of through carriers between said ends 17 and the correspondingly beveled ends 19 of the rails of track 2 at this point.

The respective ends 17 and 19 are held firmly in fixed relationship to each other by an extended ear or lug 20' of a bracket 20 which also carries idler 6. The upright portions 14 are preferably mounted in sockets 21, carried by the track bracket 22, and are inclined inwardly and bent forwardly as shown in Figs. 2 and 6, so that their free ends extend inside of the gage of track 2 by about the width of a rail, on each side. If desired, since portions 14 may be quite short, in order to impart sufficient flexibility thereto, said portions may be cut away or flattened as at 23 (see Fig. 2); and since the material of which the rails of all of the tracks are constructed is preferably steel, the portions 2' and the uprights 14 are resilient and hence admirably adapted to act as springs.

The track 2 is preferably dipped as at 24 to enable through carriers to be reengaged with the cable at this point in the manner hereinafter described; and the upper track 1 is cut away and apertured or spread at 25, in a known manner, to enable the carriers to be removed therefrom by the selective switch.

All through carriers or those intended to pass by or over the station via track 2 are disengaged from the cable by a cam 26 and hence traverse section 2' by momentum, riding off of the ends 16 thereof onto the rails of track 2 beyond the gap between sections 2' and 14' and dipping down at 24 so that their grips may be reengaged with the cable by a cam 27.

A movable cam or grip releasing device 28 is pivoted to bracket 29 and is actuated by a lever 30, mounted on its spindle 31.

Lever 30 is raised and lowered by a link

32, connected to an arm 33 upon the end of a rock shaft 34. The latter is normally turned clockwise, as viewed in Fig. 2, until arrested by a stop projection 35 on the pivoted arm 30, by a spring 36 upon said shaft; and depending from the latter are arms 37 which support a member 38 which normally is disposed in the path of through carriers and is swung aside by each of the same.

When a carrier *en route* up track 10 would collide with a through carrier at the switch, the cam or trip 28 will have been swung inwardly toward the cable from a position where it would normally clear the pivoted element of the grip of the ascending carrier to one where it will open said grip. The carrier on track 10 will then drop back until its said grip element engages a grip closing cam 39 which reengages the carrier with the cable to again elevate it toward the switch. If by this time no carrier is in contact with rod or member 38, the so re-despatched carrier will clear cam 28 and will be delivered to track 2, its flange 40 of fiber or the like, provided in carriers of this description, wiping against the switch supports 14 and as the in-bent portions of the latter are encountered these supports are pressed apart which spreads the track sections 2' and so permits the carrier to ride up quite noiselessly therebetween on to track 2. Of course said carrier thereafter passes cam 27 but its grip is already in engagement with the cable so that it need not actually quite touch said cam and hence its passage past this point is again almost noiseless.

The engagement of the fiber flange with the spreading supports 14 is also practically noiseless owing to the fact that metal is not striking against metal and further owing to the very gradual inward slope of supports 14 at this point. In fact the entrance of the carrier into the switch may be properly said to wedge the section 2' thereof quite gradually and smoothly apart; and after the emplacement of the carrier on track 2, the resiliency of the parts 2' and 14 returns them to their normal position in such manner that no stop need be provided since the parts have a bias, of themselves, to move into their normal and predetermined positions. Hence, as the stoppage of a carrier being despatched, by the movement of cam 28 into its path as the result of the disposition of a passing through-carrier upon a particular short length of track 2, occurs normally but comparatively seldom in the operation of the system in a store, practically the only appreciable noise of the apparatus is that occasioned by the opening and closing of the grips of the through carriers as they pass each station, and this noise is but slight: being but a slight click. Even when a carrier on track 10 is forced to drop and reengage the cable such noise

is not objectionable and as stated above normally occurs but occasionally.

The elimination of the abrupt opening, by the impingement of carriers thereagainst, and the snapping to against stops of the switch elements, therefore results in rendering the system relatively quite noiseless while at the same time the switch construction is simplified and the apparatus rendered more attractive in appearance.

There only remains to be described the modification of the switch embodied in the apparatus shown in Figs. 7, 8, etc. Herein, instead of integrally connecting the switch parts 2' to the track 2, separate elements 41 are provided which are each pivoted at 42 to sections of said track 2. As in the former case, supports 43 are connected by brackets 15 to switch parts 41; but said supports are 20 pivotally connected at 44 to the bracket 22' so that there is no inherent tendency for the sections 41 to normally dispose themselves in position to properly guide a through carrier past the station. Instead the switch parts 41 have connected thereto lugs 45 which move therewith as indicated by dotted lines in Fig. 10; the inner ends of these lugs being adapted to abut against stops 46, of rubber or the like which project out from an extension 47' at the lower end of the track bracket 47. Each lug 45 has an ear 45' which is apertured for the reception of an end of a coiled spring 48 which tends to hold said lugs against their 35 stops 46. The action of the switch, in so far as the passage of a carrier therethrough or thereover is concerned, is obviously substantially the same as in the preceding case. The previously described construction is to 40 be preferred however, not alone on account of its simplicity but further on account of its dependability as demonstrated in practice.

The carriers may be of any desired construction but I prefer to use those, now in common use, of the type described in my Letters Patent No. 960,617, dated June 7, 1910, wherein the grip of the carrier comprises a fixed and a pivotally mounted jaw 50 adapted for engagement with the several grip opening or closing trips or cams hereinbefore referred to.

In conclusion I may state that in the claims appended hereto I have used the term 55 "spread" in the sense in which this term is usually applied to rails of any description, and that where reference is made to a companion rail such rail is one which extends in substantial, but not necessarily actual, parallelism with the rail to be spread or moved away therefrom. Further, I desire to direct attention to the fact that the switch supports 14 act as auxiliary guides, supplementing the auxiliary track leading up from 60 the station, to steady the delivery of car-

riers from the latter to the main track 2. The tracks 1, 2 and 10 are of course preferably all of substantially the same gage, and the carrier traversing any one of said tracks does so in actual engagement therewith, the carrier moving endwise along or on the track 10 in the same manner that it rides along the tracks 1 or 2.

Having thus described my invention what I claim is:

1. Cable carrier apparatus comprising two substantially tangentially disposed tracks of approximately the same gage, a carrier to ride end foremost directly on and successively upon said tracks, means for propelling said carrier along one at least of said tracks, one of said tracks having a portion of a rail thereof adapted to be spread away from a companion rail thereof to admit of the emplacement of a carrier upon said last mentioned track, and means for spreading said portion for the purpose aforesaid as said carrier, when about to be delivered from one to the other of said tracks, approaches the point of tangency. 90

2. Cable carrier apparatus comprising a drop-station, a track extending past said drop-station and having a section thereof adapted to guide carriers thereover onto an adjoining section, said sections being discontinuous, means at said drop-station for elevating a carrier to said track and for moving apart portions of the rails thereof in a substantially horizontal plane to permit of the emplacement of said carrier upon 100 said adjoining section, and means for preventing said spreading apart of said rails when a through carrier, *en route* past said station, would engage said portions when in their spread condition. 105

3. Cable carrier apparatus comprising a drop-station, a track extending past said drop-station and having a section thereof adapted to guide carriers thereover onto an adjoining section, said sections being discontinuous, means at said drop-station for elevating a carrier to said track and for moving apart portions of the rails thereof in a substantially horizontal plane to permit of the emplacement of said carrier upon 110 said adjoining section, and means for preventing said spreading apart of said rails when a through carrier, *en route* past said station, would engage said portions when in their spread condition, said preventing 120 means including provisions for disengaging from said elevating means the carrier being propelled thereby.

4. Cable carrier apparatus comprising a drop-station, a track extending past said 125 drop-station and having a section thereof adapted to guide carriers thereover onto an adjoining section, said sections being discontinuous, means at said drop-station for elevating a carrier to said track and for 130

moving apart portions of the rails thereof in a substantially horizontal plane to permit of the emplacement of said carrier upon said adjoining section, means for preventing 5 said spreading apart of said rails when a through carrier, *en route* past said station, would engage said portions when in their spread condition, said preventing means including provisions for disengaging from 10 said elevating means the carrier being propelled thereby, and means for thereafter automatically reengaging said carrier with said elevating means.

5. Cable carrier apparatus comprising a 15 drop-station, a main track extending past said drop-station and having a section thereof adapted to guide carriers thereover onto an adjoining section, and means at said drop-station for guidedly elevating a carrier 20 to said track and for moving apart portions of the rails thereof in a substantially horizontal plane to permit of the emplacement of said carrier upon said adjoining section, said means including an auxiliary track extending up to said main track and curved 25 around at its upper end substantially into tangency with the line of said main track to deliver carriers to said main track end foremost.

30 6. Cable carrier apparatus comprising a drop-station, a main track having a section thereof adapted to guide carriers thereover part said station, and means at said drop-station for guidedly elevating a carrier to 35 said track and for moving a portion of a rail thereof away from a companion rail to permit of the emplacement of said carrier upon said main track, said means including a curved guide along which said 40 carriers travel end foremost, the line of curvature of said guide at its upper end being substantially tangent to the line of the main track at such point.

45 7. Cable carrier apparatus comprising a drop-station, a main track having a section thereof adapted to guide carriers past said station, a second track section having an end thereof curved around to deliver carriers end foremost from said drop-station to said 50 main track, said first mentioned section having a yieldingly mounted rail thereof adapted to be spread away from a companion rail at a determined point in said main track by the passage of a carrier over said second 55 sections, means to propel carriers along one at least of said sections, and means operatively connected to said yieldingly mounted rail to spread the same as said carrier traversing said second section approaches said 60 first rail section.

65 8. Cable carrier apparatus comprising a drop-station, a main track having a section thereof adapted to guide carriers past said station, a track section of substantially the same gage as said main track and having

means to deliver carriers endwise from said drop-station to said main track, said first mentioned section having a rail thereof yieldingly supported laterally, for a part of its length to adapt it to be spread away 70 from a companion rail at a determined point in said main track, and means to propel a carrier along at least one of said sections and to spread said rail in manner aforesaid.

9. Cable carrier apparatus comprising a 75 drop-station, a main track having a section thereof adapted to guide carriers past said station, an auxiliary track section to deliver carriers from said drop-station to said main track, said auxiliary track section having 80 the upper end thereof curved around to deliver carriers traversing the same endwise to said main track, one of said sections having a rail thereof adapted to be moved laterally with respect to a companion rail to permit the passage of a carrier past a determined point in one of said tracks, a yielding support for said movable rail permitting it to move in manner aforesaid, and means to propel said carrier past said determined 85 point.

10. Cable carrier apparatus comprising a station, a main track adapted to convey carriers past said station, a track to deliver carriers to said main track through and between the rails of said main track, means for propelling a carrier along said second track to said main track, auxiliary guides for said carrier, and movably mounted rigid connections between said guides and parts 100 of said main track adjacent the point of delivery of the second mentioned track to said main track.

11. Cable carrier apparatus comprising a station, a main track adapted to convey carriers past said station, a track to deliver carriers to said main track through and between the rails of said main track, means for propelling a carrier along said second track to said main track, auxiliary guides for said carrier, and operative connections between said guides and parts of said main track adjacent the point of delivery of the second mentioned track to said main track.

115 12. Cable carrier apparatus comprising a station, a main track adapted to convey carriers past said station, guiding means to deliver carriers to said main track through and between the rails of said main track, means for propelling a carrier along said 120 guiding means, and movably mounted operative connections between a part of said main track and a part of said guiding means.

125 13. Cable carrier apparatus comprising a drop-station, a track extending past said drop-station and having a section thereof adapted to guide carriers thereover on to an adjoining section, means at said drop-station for elevating a carrier to said track and 130

for moving apart portions of the rails thereof to permit of the emplacement of said carrier upon said adjoining section, and means for preventing said spreading apart 5 of said rails when a through carrier *en route* past said station would engage said portions when in their spread condition.

14. Cable carrier apparatus comprising a drop-station, a track extending past said 10 drop-station and having a section thereof adapted to guide carriers thereover on to an adjoining section, means at said drop-station for elevating a carrier to said track and for moving at least one of the rails 15 thereof relatively with respect to a companion rail to permit of the emplacement of said carrier upon said adjoining section, and means for preventing said movement of said rail with respect to its companion 20 rail when a through carrier, *en route* past said station, would engage the so moved rail when in its displaced position.

15. Cable carrier apparatus comprising two substantially tangentially disposed 25 tracks of approximately the same gage, a carrier to ride end foremost directly on and successively along said tracks, means for

propelling said carrier along one at least of said tracks, one of said tracks having a laterally movable portion of a rail thereof 30 adapted to be spread away from a companion rail thereof by the passage of a carrier end foremost past a part of the path of travel of said last mentioned carrier.

16. Cable carrier apparatus comprising 35 two substantially tangentially disposed tracks of approximately the same gage, a carrier to ride end foremost directly on and successively along said tracks, an endless cable for propelling said carrier along one 40 at least of said tracks, one of said tracks having a laterally movable portion of a rail thereof adapted to be spread away from a companion rail thereof by the passage of a carrier end foremost past a part of the path 45 of travel of said last mentioned carrier and while the latter is directly in engagement with said cable.

In testimony whereof I have affixed my signature, in the presence of two witnesses. 50
